UNITED STATES PATENT OFFICE.

HENRY P. ROBERTS, OF JAMESTOWN, NEW YORK, ASSIGNOR OF THREE-FOURTHS TO A. F. ALLEN BROWN, GEORGE S. GIFFORD, AND MARTHA B. MARSHALL.

VAPOR STOVE AND BURNER.

SPECIFICATION forming part of Letters Patent No. 399,212, dated March 5, 1889.

Application filed August 9, 1888. Serial No. 282,310. (No model.)

To all whom it may concern:

¶ Be it known that I, HENRY P. ROBERTS, a citizen of the United States, residing at Jamestown, in the county of Chautauqua and State 5 of New York, have invented a new and useful Improvement in Vapor Stoves and Burners, of which the following is a specification.

My invention relates to an improvement in vapor burners and stoves adapted to burn 10 crude petroleum or other hydrocarbon; and it consists in the peculiar construction and combination of devices, that will be more fully set forth hereinafter, and particularly pointed out in the claims.

15 In the accompanying drawings, Figure 1 is an elevation of my improved vapor-stove. Fig. 2 is a vertical sectional view of the same. Fig. 3 is a detached inverted plan view of the retort or generating-chamber. Fig. 4 is a detailed perspective view of a modified form of the same, showing a number of burners depending therefrom. Fig. 5 is an enlarged 20 vertical longitudinal sectional view of the retort, the supply-pipe, and the burner. Fig. 6 is an enlarged detailed vertical central sectional view of my improved vapor-burner.

A represents a hollow standard, which forms the base of the stove, and is of the form here shown, and is supported by legs B. At the 30 base of the standard are a series of air-inlet openings, C. The central portion of the standard is contracted to form a neck, D, in which is located a pivoted damper, E. The upper end of the hollow standard is enlarged 35 to form a bell-shaped circular hollow table, F, from the center of which projects a vertical inverted conical combustion-chamber, G. The same is provided on one side with a hinged door, H, by means of which access 40 may be obtained to the interior of the combustion-chamber. The latter communicates at its lower end with the hollow standard, as shown in Fig. 2.

Supported on the upper end of the combustion-chamber G is a drum or oven, I, the same 45 being cylindrical in shape, as here shown, or of any other preferred form. On one side of the said drum or oven is a door, K.

L represents a retort or vapor-generator 50 the central portion of which is circular in

shape, as at M, Fig. 4, and the said retort is provided with arms N, which project in diametrically-opposite directions from the central portion, M, and rest upon the bottom of the drum or oven I, and serve to support the 55 circular portion M above the combustion-chamber B and concentric therewith, so as to leave an opening between said combustion-chamber and the drum or oven, as shown in Fig. 2. The sides of the central portion, M, 60 of the retort converge downward till they meet, as shown in Figs. 4 and 6, and thereby the said central portion of the retort is provided with a maximum amount of heating-surface. Arranged directly in the center of 65 the retort is an inverted conical cap or chamber, O, which is supported by a pair of bridge-arms, P, that are arranged at right angles to the arms N, and are provided with longitudinal openings, which establish communication 70 between the portion M of the retort and the cap O. In the lower side of the cap O is screwed a bushing, R.

S represents a vertical cylindrical burner, the upper end of which is conical and is provided with a central ascending stem or pipe, T, the upper end of which is screwed into the bushing R, so as to suspend the burner from the cap, as shown in Figs. 2, 3, and 6. The bore of the said stem or pipe is reduced at its 75 lower end, where it communicates with the upper end of the mixing-chamber Z², formed in the burner, so as to form a minute channel, U, to introduce vapor in a jet having considerable velocity to the interior of the burner. 80 The conical upper side of the burner is provided with air-inlet openings V, and near the base of the burner are escape-openings W for the commingled air and vapor. The base of the burner is provided with a central cone, 85 X, the axis of which is directly in line with the channel U, and the said base is further provided with an annular concavity or recess, Y, which surrounds the base of the cone and is of suitable depth, as shown in Fig. 7.

Z represents a diaphragm or plate, which 90 is arranged in the burner at a suitable distance from the base thereof, and is substantially concavo-convex, with the concaved side down, and is provided with a central opening, 95 100

A', which is concentric with the cone and through which the apex of the latter projects.

B' represents a stand or supply pipe, which communicates with the retort and with a suitable reservoir for oil, (not shown,) and is provided with a needle-valve, C', for regulating the quantity of oil fed to the retort.

The table F is provided at diametrically opposite points in line with the arms N of the retort with openings D', in which are inserted the bowls of lamps E', of suitable construction. The said lamps are provided with chimneys F', which serve to concentrate the heat from the lamps under the arms N of the retort in order to heat the latter sufficiently to convert the oil therein into vapor when it is desired to start the burner in operation.

An escape-pipe, G', for the products of combustion communicates with and extends from the oven or drum I.

The operation of my invention is as follows: The damper E being opened, atmospheric air is admitted to the hollow standard A through the openings C and ascends through the said standard. The valve C' being opened, oil is supplied to the retort from the reservoir, and the heat from the lamps F' converts the oil into vapor, as before stated, and the vapor is forced by its own expansion through the cap O and the stem or pipe T and through the contracted channel U into the burner, and is caused to impinge against the sides of the cone X. From the said sides of the cone the vapor is deflected to the bottom of the concavity or recess Y, and from the same the vapor is deflected upward at an angle of about thirty-five degrees (from the perpendicular) through the openings W. As the vapor thus passes downward through the burner and outward through the openings W thereof, a partial vacuum is formed in the burner, and hence air is sucked into the same through the openings V in the upper end of the burner. The plate or diaphragm Z causes the air to eddy in the burner and become commingled in such quantities with the vapor, as the latter descends through the burner, as to render the vapor highly combustible, and the commingled air and vapor which escape through the openings W are ignited and burn in a bluish flame of great heat and brilliancy.

It will be evident that after the burner is started in operation the retort will be maintained at such a temperature as to cause the same to convert the oil to vapor as rapidly as the oil is supplied thereto, and hence the use of the lamps E' may be discontinued. The air which is sucked into the openings V of the burner must first pass through the flame, and hence becomes highly heated, and thus caused to commingle more readily with the vapor in the burner and also assist in maintaining the latter at a high degree of temperature before it becomes ignited.

The air which ascends through the standard A is caused, by the contracted combustion-chamber G, to be thrown into intimate

association with the flame from the burner, and hence becomes highly heated before passing into the oven or drum I.

The tarry residuum from the oil is carried by the vapor and dashed against the sides of the cone and deflected outward to the openings W in the form of spray and burned together with the vapor; hence no portion of the oil is wasted, and the burner is therefore adapted to generate the maximum amount of heat with a minimum consumption of oil. Another advantage resulting from the peculiar construction of the burner is that the same does not become so readily clogged and fouled with the products of combustion as the burners now in common use, and hence my improved burner does not require to be cleaned so often.

It is not essential to the operation of my burner that the same be inclosed in a combustion-chamber. On the contrary, the burners will operate successfully in the open air.

In Fig. 4 I illustrate another mode of using my vapor-burner, in which a number of the burners depend from a retort, H', which is rectangular in form, and is also provided with a central bridge-arm, I', the sides of said arm and of the rectangle converging downward, as shown, so as to form a maximum extent of heating-surface, in a manner similar to that employed in the construction of the retort L, hereinbefore described.

Vapor-burners thus constructed are adapted to be used not only in stoves for heating and cooking purposes, but may be also employed in the furnaces of steam-boilers for generating steam.

Having thus described my invention, I claim—

1. The vapor-burner comprising the case having the mixing-chamber Z² formed in its interior, the feed-channel U and air-inlet openings communicating with the upper end of said mixing-chamber, the escape-openings W at the lower end of said mixing-chamber and communicating directly with the outer air, and the cone X, rising from the bottom of the case, substantially as described.

2. The burner having the opening U in its upper end for the admission of vapor, the air-inlet openings at its upper end, the cone X, projecting from the base of the burner, the annular groove Y, surrounding the base of the cone, the escape-openings W in the sides of the burner near its base, and the diaphragm or plate Z, arranged in the case and having central opening, A', through which the apex of the cone projects, substantially as described.

3. The vapor-burner comprising the casing S, having the vapor-supply channel U and the air-inlet openings V in its upper end, the escape-openings W near its base, the cone X, projecting from its base, and the plate or diaphragm Z, arranged in the case and having the central opening, A', in combination with the combustion-chamber, in which the burner is arranged, and means, substantially as speci-

fied, to supply the combustion-chamber with an ascending current of air, substantially as described.

4. The vapor-stove having the combustion-chamber G and the drum I, in combination with the retort arranged in the drum, the burner depending from the retort and arranged in the chamber G, and the lamps E' on the outer side of the chamber G and arranged under 10 the retort, substantially as described.

5. The vapor-stove comprising the hollow standard A, communicating at its lower end with the outer air, the table F at the upper end of said standard, the contracted combustion-chamber G, rising from the table, and the drum or oven I above said combustion-chamber, in combination with the retort and the burner depending therefrom, the said burner being located in the chamber G, substantially 15 20 as described.

6. The combination of the vapor-stove having the hollow standard A, with the openings C at its base, and the contracted neck B, the combustion-chamber rising from and communicating with the hollow standard, the drum or 25 oven above and communicating with the combustion-chamber, the retort, the burner depending therefrom and arranged in the combustion-chamber, and the damper E in the neck of the standard, substantially as de- 30 scribed.

In testimony that I claim the foregoing as my own I have hereto affixed my signature in presence of two witnesses.
